UNITED STATES PATENT OFFICE.

ENRIQUE G. DOERING HARMSEN, OF HACIENDA SAUSAL, VIA TRUJILLO, PERU.

POCKET LEVEL.

Application filed September 24, 1920. Serial No. 412,595.

To all whom it may concern:

Be it known that I, ENRIQUE G. DOERING HARMSEN, a citizen of Peru, residing at Hacienda Sausal, via Trujillo, Peru, South America, have invented certain new and useful Improvements in Pocket Levels, of which the following is a specification.

This invention relates to a combined level and angle measuring instrument so constructed that the parts may be folded into compact form for easy transportation and which, at the same time, affords the same degree of accuracy when in operation as may be obtained by the use of heavier and more complicated instruments.

This invention further relates to improvements in the type of instrument disclosed in my co-pending application Serial No. 412,596, filed Sept. 24, 1920, said improvements being directed more particularly to the mounting of the various parts so that horizontal and vertical angles may be read with regard to the point over which the tripod carrying the instrument is positioned.

This invention also provides an improved sighting device in the form of a prism mounted in a recess of a pivoted arm.

Other advantageous features of the invention will be apparent upon reference to the specification which refers to the accompanying drawings.

In the drawings:

Figure 1 represents a top plan view of the assembled device with a part in section to disclose the tripod pivot pin;

Figure 2 is a section on the line 2—2 of Figure 1, looking in the direction of the arrows;

Figure 3 is a section on the line 3—3, Figure 1, looking in the direction of the arrows;

Figure 4 is a side elevation of the assembled device showing the movable arm in several positions;

Figure 5 is a partial sectional view of the device in folded position.

The numeral 10 designates a folding member preferably in the form of a circle graduated to 360°. As shown, the folding member is made in two parts divided along the line 12—12 and these parts are preferably hinged, the hinges being shown diagrammatically in dotted lines at 11, Figure 1. Each of the two parts of the member midway of the length of its hinged edge has a semi-circular notch, and these notches of the

two parts are adapted to embrace a pivot pin 13 attached to a tripod or other suitable support (not shown). It will be understood that clamping means (not shown) may be provided for clamping the member 10 in any adjusted position and also that means may be provided for adjusting the horizontal position of the member 10 or tripod so that the member 10 will be level when the instrument is in operation.

A base 14 is provided with an enlarged end 15 preferably circular in form, said end being formed with a recess adapted to receive the upper end of the pivot 13 of the tripod. A recess 16 is formed in one edge of the base 14 and the vertical side wall 17 of said recess serves as an indicator with respect to the graduations on the member 10. One edge of the base 14 at the free end thereof is cut away so as to form a recess 18 limited by the walls 18 and 19. The base is further provided with a recess 20 extending across its upper surface having one of its surfaces 21 inclined at an angle of about 45°. Holes 22 are also formed through the base and countersunk at their upper extremities in order to receive suitable fastening devices for securing the base 14 to a support when it is used independently of the circular member 10.

An arm 23 is pivotally mounted to the enlarged portion 15 of the base by means of a threaded pivot 24, the axis of which is in the same plane and perpendicular to the axis of the pivot pin 13 of the tripod. The arm 23 is provided at one end with a centrally projecting circular portion 25 that engages the pivot 24. The arm may be turned about the pivot 24 and is retained in adjusted position by means of the nut 26 which may bind or release the arm in the well known manner.

The arm is also provided with recesses adapted to receive a compass case 29, which is adjustably secured in the casing by the threaded stud 27, and also a level that is preferably inserted in the arm from the lower side thereof and retained in place by projecting shoulders 32, retaining plate 30 and fastening devices 31. The free end of the arm 23 is formed with a downwardly projecting portion 33 having an inner surface inclined at the same angle as the surface 21 of the base. The upper portion of the free end of the arm 23 is partially cut

away at 34, the recess being terminated by the member 35 which forms a continuation of the body of the arm. A strip 36 is secured to portion 35 of the arm by means of 5 suitable fastening devices 37 and is formed at one extremity with a boss 38 preferably internally threaded so as to receive a thumb screw 39 adapted to be inserted through a slot in the graduated arc-shaped member, as 10 will hereinafter appear.

A graduated arc-shaped member 40 is pivoted at one end to the base 14 preferably at the surface 19 of the end recess by means of a threaded stud 41 and adjusting nut 41' 15 engaging the same for the purpose of releasing or binding the graduated arm 40 so that it may be placed in either operative or folded position. The arc-shaped member 40 is also provided with a longitudinal 20 arcuate slot 42 through which the screw 39 may be inserted.

The projecting portion 33 of the arm 23 is recessed at one side, as above described, and in this recess 34 is inserted a prism-sight 25 preferably composed of glass plates 44 and 45 and a silvered reflecting surface 46. It will be understood that the plates 44 and 45 have cross-lines marked or etched thereon, as shown in Figure 1. A slotted 30 pointer 46^a also secured to the projecting portion of the arm 23 cooperates with the arc-shaped member 40 to indicate the inclination of said arm. The base 14 has an angular cut 48 near one end, and the projecting portion 33 of the arm also has a slot 47 cut therein at a corresponding angle in order to provide clearance so that the arm 40, when thumb-screw 39 is temporarily removed, may be folded into compact relation with the other parts of the device. 40

It will be noted that the axes of the pivot 24 and the vertical pivot pin 13 of the tripod are in the same vertical plane and at a right angle to one another and also that 45 the point of intersection of the cross-lines of the plate 45 is in the same plane with the horizontal axis of the pivot 24 and with the indicating surface of the pointer 46^a. It will also be noted that the indicating surface 17 of the base is in the same vertical plane as the axis of the pivot pin 13 of the tripod. This construction enables the 50 measurements of vertical and horizontal angles to be both referred to the point over which the tripod is positioned. In reading vertical angles the object is sighted through the prism side plates and the arm is adjusted in position until the image appears 55 symmetrically about the intersecting points of the cross-lines, when the arm may be secured in position by means of the adjustable nut 26 and the angular inclination indicated by the position of the pointer 46^a on the graduated forward face of the arc-shaped member 40. The opposite side of 60

the arc-shaped member 40 is preferably graduated into natural sines so that the sine of the angle of inclination may also be readily obtained. In reading horizontal angles the objects are sighted through the prism sight 43 in the same manner, pivot arm 23 being first moved to closed position, in which position it should be level as indicated by the level on the arm 23. The 70 readings on the member 10 corresponding to the positions of the vertical surface 17 will indicate the horizontal angle between the objects sighted. 75

To fold the parts for easy transportation, the base and circular member are removed 80 from the pivot of the tripod after which the two sections of the circular member may be folded into contact about their hinged connection. The thumb-screw 39 may be removed and the arm and arc-shaped member folded to the relative positions shown in Fig. 5. The screw 39 can then be inserted through the opposite side of lug 38 or kept conveniently in a case provided to receive the folded instrument. 90

I claim:—

1. In an angle measuring instrument adapted to be used with a tripod having a vertical pivot pin, a foldable member mounted at its center about said pin, a base 95 mounted on said pivot pin and superposed on said member, an arm, a horizontal pivot for said arm at one end of said base with its axis in the same vertical plane with and at a right angle to the axis of said pivot pin, a graduated arc-shaped element pivotally mounted at the other end of said base, and a pointer carried by the free end of said arm and cooperating with said graduated element for indicating the inclination 100 of said arm, the indicating surface of said pointer being in the same plane with the axis of said horizontal pivot, said base having a vertical wall in a vertical plane with the axis of said pivot pin and cooperating 105 with graduations on said member whereby horizontal and vertical angles may be measured with respect to the center of said base. 110

2. In an angle measuring instrument, a base having a recess formed therein, an arm having a projection adapted to fit into said recess, means for pivotally connecting said arm to said base adjacent one end of the latter, said arm having a recess in said projection, a right angle prism mounted in said recess, the incident and emergent surfaces of said prism having cross-lines marked thereon, a pointer carried by the free end of said arm, a graduated arc-shaped element detachably carried by said base adjacent its opposite end with which said element and pointer cooperates to indicate the inclination of said arm, the indicating surface of said pointer, the point 115 120 125 130

of intersection of the cross lines on the incident surface of said prism, and the axis of said pivot being in the same plane.

3. In an angle measuring instrument 5 adapted to be used with a tripod having a vertical pivot pin, a graduated member having an aperture to receive said pin, a base pivotally mounted at one end on said pin, an arm, means for mounting said arm for 10 swinging movement at said end of the base, said means having a horizontal axis, a right angle prism carried by the free end of said arm having its incident and emergent surfaces marked with cross-lines, the point of 15 intersection of the cross-lines on said incident surface being in the same plane with said horizontal axis and in a vertical plane containing the axis of said pivot pin, and means carried by said base and associated 20 with said arm for indicating the inclination of the arm, said base having an indicating means cooperating with said graduated member for indicating the horizontal angular position thereof.
4. In combination, a base adapted to be 25 mounted for movement in a horizontal plane, an arm connected to said base adjacent one end of the latter for movement in a vertical plane, the axes of movement of 30 said base and arm lying in vertical relation to one another, a graduated arc-shaped element carried by the other end of said base, said element having an arc-shaped slot extending longitudinally thereof, a strip 35 carried by the free end of said arm, and means adjustably engaging said strip and passing through said slot for securing said arm in adjusted position.
5. In combination, a circular member, a 40 base, an arm mounted on said base for swinging movement, the axis of movement of said arm lying above the center of said member, an arc-shaped element carried by the base and foldable against the latter, said 45 arc-shaped element adapted, when in oper-

ative position, to indicate the inclination of said arm, and a sighting prism supported by said arm having faces perpendicular to one another and exposed, respectively, upwardly and toward the free end of said arm. 50

6. In combination, a foldable member having a central hole to receive a vertical pivot pin, a base pivotally mounted on said pin and superimposed on said member, an arm, a horizontal pivot for mounting said 55 arm on said base to permit said arm to be folded into contact with the upper surface of the base, a sighting prism carried by said arm having cross-lines on its incident and emergent surfaces, a graduated arc-shaped 60 element pivoted to said base, a pointer carried by said arm and associated with said graduated arc-shaped element, and indicating means on said base, one of the cross-lines of said incident surface being in the 65 same plane with said indicating means and the axis of said vertical pivot, and the other cross-line being in the same plane with the indicating surface of said pointer and the axis of said horizontal pivot. 70

7. In combination, a foldable graduated member adapted to be mounted on a tripod, a base pivotally mounted on the said member, an arm pivotally mounted on said base with its pivotal axis lying above the pivot 75 of said base on said foldable member and said arm being adapted to be folded into contact with the upper surface of said base, an arc-shaped graduated element also pivotally secured to the base and adapted to 80 be folded into contact therewith, and a level and sighting prism carried by said arm.

In testimony whereof I have hereunto set my hand in presence of two subscribing witnesses.
